UNITED STATES PATENT OFFICE.

HENRY D. METCALF, OF CASEY, ILLINOIS, ASSIGNOR OF ONE-HALF TO GLENN DOUGHERTY, OF CASEY, ILLINOIS.

FLUID-CONTROLLING DEVICE.

1,212,085.

Specification of Letters Patent.

Patented Jan. 9, 1917.

Application filed November 28, 1914, Serial No. 874,499. Renewed December 1, 1916. Serial No. 134,503.

To all whom it may concern.

Be it known that I, HENRY D. METCALF, a citizen of the United States, residing at Casey, in the county of Clark and State of Illinois, have invented new and useful Improvements in Fluid-Controlling Devices, of which the following is a specification.

An object of the invention is to provide a device for use in controlling the flow of 10 fluids, the device being particularly adaptable for use in controlling, by a pressure of the foot, the flow of hot and cold water or the draining of water from a basin, as in bath rooms, barber shops and the like.

15 The invention contemplates, among other features, the provision of a device which is operated by the foot and which, therefore, gives perfect freedom to the hands of the operator so that when the device is used in connection with a bath room wash bowl or the like, the operator can wash his hands without necessitating the use of one of the 20 hands in operating the device.

Still further embodiments of the invention reside in a device which permits of supplying hot or cold water to a wash bowl or combining hot and cold water, while at the same time provision is made for flushing the wash bowl with hot water, with cold 25 water or with a combination of hot and cold water. Although the device can be used for various purposes for controlling the flow of fluids into a receptacle so that one fluid can be combined with another or supplied to the 30 receptacle by itself without combining with another fluid, I particularly employ my device in connection with bath room structures and toilet constructions, the principal object being to set forth a structure which 35 enables the operator to freely use his hands by having the device foot controlled.

In the further disclosure of the invention reference is to be had to the accompanying drawings, constituting a part of this specification, in which similar characters of reference denote corresponding parts in all the 40 views, and in which:

Figure 1 is a perspective view of the device as used in connection with a wash bowl; 45 Fig. 2 is a vertical sectional view of the structure shown in Fig. 1; Fig. 3 is a fragmentary enlarged vertical sectional view of the supply valves; Fig. 4 is a fragmentary enlarged vertical sectional view of the drain 50

valve; Fig. 5 is a fragmentary perspective view of one of the lever connections; and Fig. 6 is a fragmentary vertical sectional view taken through a modified form of operating member.

Referring more particularly to the views, I disclose the usual wash bowl or receptacle 10 supported in any suitable manner by brackets 11, upon a wall 12. The wash bowl 10 has an outlet 13 to which is connected a drain pipe 14 having the usual trap 15, and arranged in the drain pipe is a valve 16 for controlling the draining of fluid from the receptacle or bowl 10. A pipe 17 is suitably supported on the bowl, said pipe being in the nature of a discharge to the bowl and connecting with a casing 18 formed with a compartment 19 common to a plurality of valve chambers 20 in the casing, each of which is normally closed to the compartment 19 by a spring-actuated valve 21, each of said compartments 20 having communication with a fluid supply pipe 22, one of said supply pipes preferably carrying hot water and the other cold water. Now it will be clearly seen that when one of the valves 21 is open a supply of hot water will be delivered to the bowl or receptacle 10, whereas when the other valve is open a supply of cold water will be delivered to the receptacle, said supplies of water being adapted to pass through the single discharge pipe 17 and which has the two pipes 22 common thereto through the medium of the compartment 19.

In order to effect a proper operation of the device by means of the foot each of the valves 21 carries a stem 23 passing upwardly and outwardly through the valve casing and which, when subjected to a downward pressure, opens the valve against the action of the spring thereof. The valve casing carries a plurality of standards 24 and arranged to swing on each standard and centrally pivoted thereon is a link 25, one end of said link being connected with the stem and the other end connecting with a rod 26 having its lower end passing through a plate 27 formed to constitute a part of the usual floor 28 and in pivotal connection with one end of a bell crank lever 29. The bell crank lever 29 is supported to swing upon an upright 30 and has its other end connecting with a link 31

which in turn is also pivoted to one end of a second bell crank lever 32 mounted to swing upon an upright 33. The bell crank lever 32 has connection by means of a suitable link 34 with a lever 35 pivoted upon an upright 36 and which in turn is connected with a link 37 pivoted to an operating member 38 passing upwardly through the plate 27 and terminating in a knob 39 upon which the pressure of the foot is adapted to bear, said operating members being supported in a suitable guide 40 common to both members, as shown.

Now as mentioned heretofore the valves 21 are normally closed and when it is desired to open the valve which controls the supply of hot water to the bowl or receptacle, a downward pressure of the foot is applied to one of the operating members 39 and thus through the medium of the levers and link connections described actuating the rod 26 and which, through the medium of the link 25 and stem 23 operates the valve to open the same and permit a supply of hot water to pass through the discharge pipe 17 into the bowl or receptacle 10. Similarly, the other operating member can be actuated to operate the other valve 21 and supply cold water to the receptacle through the medium of the discharge pipe 17 and in view of the fact that the two operating members are arranged adjacent to each other it will be seen that by the pressure of a single foot one or the other or both operating members can be actuated to supply hot or cold water or a combination of both, the hot and cold water supply pipes being common to the single discharge pipe 17 through the medium of the valve chambers 20 and the compartment 19.

The drain valve 16 carries a lever 41 which has pivotal connection with a rod 42 passing downwardly through the plate 27 and connecting with a lever 43 pivoted on the upright 36, said lever 43 having pivotal connection with a link 44 and which, in turn, connects with an operating member 45 also passing through the plate 27 adjacent the operating members 39 and having a knob 46, said operating member 45 being also supported in the guide 40. Now it will be seen that the supply operating members indicated by the numeral 39 and the drain operating member indicated by the numeral 45 are all adjacently arranged so that by the pressure of a single foot each can be operated independently, the three can be operated together or any two can be simultaneously operated, thus insuring every possible combination for the purpose of supplying hot water, cold water, both hot and cold water or flushing the bowl or receptacle 10 with hot water, cold water or both hot and cold water. When all three operating levers 65 are depressed it will be clearly seen that the

drain pipe will be open and supplies of hot and cold water will be delivered to the receptacle 10 so that while the receptacle is receiving the water from the discharge pipe 17 the bowl or receptacle is being flushed 70 and the fluid received therein is being carried out through the drain pipe.

The downward movement of the operating members is preferably limited by the provision of suitable stop lugs 47 and 75 which can be secured to the upright 37 or to the floor 28 in the depression formed to receive the mechanism connecting the operating members with the rods 26 and 42. It will of course be understood that I do 80 not limit myself to the specific arrangement of the various parts, and whereas the casing 18 is shown as supported by a bracket 48 upon the wall 12, the casing can be arranged in any suitable manner, behind or in front 85 of the wall and the component parts also suitably arranged in accordance with the particular kind of bowl or receptacle to which it is desired to supply a quantity of fluid. 90

In Fig. 6 there is shown a slightly modified form of operating member and in which instance the operating member is indicated by the numeral 49, includes a knob 50 on its upper end, a suitable ball 51 being preferably formed at the lower end of the operating member and arranged to repose upon a ledge 52 projecting from the front end of the lever 35 and which is preferably provided with an opening 53 through which 100 the operating member loosely extends as shown, said operating member passing loosely through the plate 27 forming a part of the floor 28.

The device is also adaptable for various 105 other purposes and need not be limited to use with toilet fixtures, it being clearly apparent that the structure described can be used for the purpose of controlling the flow of a certain fluid to a receptacle and the 110 draining thereof from the receptacle or controlling the flow of a combination of fluids to and from a receptacle.

In order to insure a proper operation of the operating members suitable springs 54 115 are provided and which are arranged to hold the operating members in normal position and insure the return of the operating members to normal position after the same have been operated by the foot and the foot removed from the knobs of the operating members. It will, of course, be understood that the springs arranged in the casing 18 to operate upon the valves 21 are not absolutely necessary in the operation of the device, particularly in cases where the city water supply is connected with the device and where the pressure of the fluid is sufficiently great to resist the valves after the same have once been opened. 125 130

Having thus described my invention, I claim:

In combination a valve having its stem projecting vertically, a centrally pivoted link having one end pivotally connected to said stem, a vertically arranged bar having its upper end pivotally connected to the remaining end of the said link, a pair of bell crank levers pivotally connected together and one further pivotally connected to the lower end of said rod, a horizontally arranged centrally pivoted lever having one

end pivotally connected to one of said bell crank levers, a vertically slideable member and a link swingingly connecting the remaining end of said horizontally arranged lever with said member.

In testimony whereof I affix my signature in presence of two witnesses.

HENRY D. METCALF.
